UNITED STATES PATENT OFFICE

EDWARD F. DARON, OF COEUR D'ALENE, IDAHO

PUMP

Application filed May 27, 1929. Serial No. 366,150.

My invention relates to pumps and more particularly to a pump that is operated by cam rocking means and wherein certain objects of the invention are to provide a pump that is made relatively high in efficiency by utilizing the laws of gravity and the forces generated thereby together with the aid of small additional forces.

With the above and other objects in view which will appear as the description proceeds, the invention consists of the novel construction, adaptation, combination and arrangement of parts hereinafter described and claimed. These objects are accomplished by devices illustrated in the accompanying drawings; wherein:

Figure 1 is a view in side elevation of the pump;

Fig. 2 is a top plan view of the same;

Fig. 3 is a view in transverse vertical section taken substantially on a broken line 3, 3 of Fig. 1;

Fig. 4 is an enlarged fragmentary view in vertical section taken substantially on a broken line 4, 4 of Fig. 3; and

Fig. 5 is a somewhat diagrammatic view in vertical section showing the course of the water through the device.

Referring to the drawings throughout which like reference numerals designate like parts, the numeral 5 indicates the frame of the pump which is mounted on a base 6 comprising a plurality of I-beams secured together. A track 7 comprising two rails is mounted on said base and is arranged for lateral displacement as more fully hereinafter set forth. Said track is adapted to be aligned with short fixed end supports 8 that are eight in number as clearly shown in Fig. 2 of the drawings.

The rocking means for the device comprises a heavy weight 9 that is provided with two sets of cams 10 and 11 respectively. These cams are adapted to ride on the track 7 and are so proportioned with respect to the frame 5 that the rocking means as a whole will make a half revolution and completely reverse its position as shown in dotted lines in Fig. 1 upon rolling from one end of the frame to the other.

The cams 10 are provided with two inches greater eccentricity at their lower ends so that when the rocking device rolls from its full line position to its dotted position it will travel down hill so to speak. Likewise the cams 11 have a corresponding eccentricity at their upper ends and will roll down hill in passing from the dotted to the full line position as will be understood. The high points of the first-named eccentrics are disposed one hundred and eighty degrees from the high points of the other pair of eccentrics. The cams 10 travel on the track 7 while in its outward or full line position as shown in Fig. 2 when the rocking device moves to the dotted position in Fig. 1, and the cams 11 travel on said track in its narrowed or dotted position when rolling back to the full line position. It will be understood that in both the full and dotted positions of said cams, as shown in Fig. 2, they are completely supported by the fixed end supports 8 and are entirely free of the track 7, leaving said track free to be shifted laterally back and forth into alternative alignment with said stationary end supports.

The means for automatically shifting the track 7 comprises a shaft or rod 12 that extends centrally between said track and is journaled to the frame 5 at both of its ends. A finger 13 is fixed to each end portion of said shaft vertically above the fixed track end supports 8. Yokes 14 are keyed to the shaft and connected to the rails of the track by links 15. Thus at the end of its stroke and when resting on said track end supports the weight 9 engages one of the fingers causing the shaft to revolve whereby the links draw the track inwardly to the dotted position, and at the end of its other stroke said weight engages the other and oppositely disposed finger whereby the track will be expanded to its original position. The track is thus caused to alternatively register with the fixed end supports in keeping with the eccentric disposition of the cams 10 and 11 as the rocking device rolls back and forth.

For the purpose of retaining the weight 9 at rest in an upright position for a short length of time at either end of its stroke, arms 16 are secured thereto and are provided with

rollers 17. Stop members 18 are secured to the upper portion of the frame 5 at either end. Said rollers glide over the tops of said stop members and roll down against their rear sides while the weight 9 is settling to its lowered position shown in Fig. 4. Thus the rollers and stop members restrain the rocking device as a whole from beginning another stroke until said weight has reached its downward limits and the rollers are then free to pass under said stop members as the weight begins its reverse movement.

As a means for stopping the rocker device I have provided a pair of hooked levers 19 that are pivoted to opposite sides of the frame 5 at 20. The hooked ends of said levers by means of their weight are arranged to alternatively engage rollers 21 mounted on the end portions of the rocker frame. A hooked arm 22 is pivoted to each of said levers and their hooked ends are arranged to alternatively catch on lugs 23 fixed to the rear of said weight. A rod 24 slidably mounted on the frame is provided with cams or fingers 25 which engage the arms 22 and hold them in the paths so that their hooked ends will engage said lugs. By pulling said rod the hooked ends of said arms are disengaged from said lugs and the rocking device will be stopped at either end of its stroke.

The weight 9 is provided with a water chamber 26 at both its upper and lower ends and said chambers are enclosed by cylinder heads 27 that are secured to the frame of the eccentrics 10 and 11. Said weight fits snugly in said cylinder heads and is free to slide up and down for reasons presently apparent. An anti-friction roller 28, mounted on the frame of the cams 10 and 11, engages the weight and helps to support it during the movement of the rocking device as will be understood.

Intake tanks 29 at either end of the machine are connected by a pipe 30 and an intake pipe 45 31 extends therefrom to the source of water supply. A discharge tank 32 is superimposed on each of said intake tanks and said discharge tanks are connected by a pipe 33 and a discharge pipe 34 extends therefrom to the point of delivery for the water. A manifold pipe 35 connects each intake tank with its associated discharge tank and a flexible hose 36 and 37 extends respectively from each of said manifolds to the upper water chamber 26 on its respective side. In other words the flexible hose 36 extends from the manifold 35 on the right to the water chamber 26 which is, for the time being, the upper water chamber when the weight 9 and its cams are at its right hand position as shown in full lines in Figs. 1 and 4, and the flexible hose 37 extends from the manifold 35 at the remote or left hand end of the device to the water chamber 26 which is the lower chamber in this particular position. Fingers 38 are

provided on the cams 10 and 11 to pick up one of said hose and at the same time lay the other hose down as the rocker device moves back and forth.

Referring to Fig. 4 of the drawings the weight 9 has completed its stroke and has moved downwardly until its lug 23 has disengaged the arm 19 from the roller 21 and said weight is ready to begin another stroke to the other side of the frame 5. Said weight in moving down has forced the water from the lower chamber 26 through the hose 37 into the discharge tank 32 on the other end of the frame. At the same time said weight in moving down has created a vacuum in the upper chamber 26 whereby said chamber has been filled with water by suction from the intake tank 29 on the right hand side.

In Fig. 5 an arrangement of flap valves is shown whereby the water is diverted from the intake tanks 29 to the discharge tanks 32. As described immediately above, the water has been drawn from the intake tank 29 on the right into the upper pump chamber 26 and an intake flap valve 39 in the manifold 35 is opened upwardly while a discharge flap valve 40 in said manifold is closed downwardly. At the same time the water has been forced from the lower pump chamber 26 into the discharge tank 32 on the left whereby a discharge flap valve 41 is opened upwardly and an intake flap valve 42 is closed downwardly. It will thus be observed that this arrangement is reciprocal in that the discharge and intake valves are alternatively opened and closed and that the positions of said valves will be reversed on the other stroke of the rocker device. The intake tanks 29 are actuated only by suction while the discharge tanks 32 are actuated by pressure and the pressure forces the water alternatively from said discharge tanks through the pipe 33 and the discharge pipe 34.

To completely carry the rocker device to the ends of its strokes a water-motor 43 is used. Said water-motor is provided with a shaft 44 supported in suitable bearings on the frame 5 and having a pulley 45 on each of its ends. Cables 46 extend from said pulleys to sheaves 47 mounted on the other end of the frame. Said cables are pivotally fastened to the rocker frame at 48 concentrically with the cams 10 and 11. To operate said water-motor a small blow pump 49 driven by an electric motor 50 is used as shown in Fig. 5 of the drawings. The water for said blow pump is taken from the discharge tank pipe connection 33 through a pipe 51 and after being forced through the water-motor 43 the water is returned to the intake tanks through a pipe 52 joined with the intake connecting pipe 30.

It will be understood that the cables 46 have no great pulling power and are primarily intended for the purpose of giving the

rocker device its initial start or movement from its state of rest at the ends of its strokes. It will also be understood that the electric motor 50 is only of sufficient power to operate the water-motor 43 to the extent of initially moving said cables. The water for operating said water-motor is already under considerable pressure, being taken from the high pressure line 33, and only small additional power is needed. The cables will be carried around, or back and forth, by the forceful movement of the heavy rocker device when same is once started from its state of rest at the ends of its strokes.

In order to reverse the water-motor 43 I have provided a valve 53 whose core 54 has a crank rod 55 extending therefrom and pivoted to a connecting rod 56 which extends the full length of the frame 5. Said connecting rod is provided at either end portion with a finger 57 and said fingers are engaged by the rocker device at each end of its stroke which causes the crank rod 55 to give the valve core 54 a quarter turn. Said valve core is provided with two longitudinal cross openings 58 which are shown in registry with the pipe connections in Fig. 5 whereby the water-motor 43 will rotate as indicated by the direction arrows. Said valve core is also provided with two transverse openings 59 disposed substantially at right angles with said crossed openings and when said valve core is given a quarter turn by the means just described said transverse openings will be brought in line with the pipe connections thus changing the direction of flow and reversing the water-motor 43 as will be understood.

I claim:

1. A pump comprising a frame, a track, a weight, a double pair of cams for the weight adapted to ride on the track, and means for shifting the track to alternatively engage the cams at either end of the frame.

2. A pump comprising a frame, a track, a double pair of cams adapted to ride on the track, means for shifting the track to alternatively engage the cams at either end of their strokes, cylinder heads mounted on the cams, a weight slidably mounted in the cylinder heads whereby a chamber is provided at either end thereof, and means for causing said weight and cams to oscillate between the ends of the frame.

3. A pump comprising a frame, a track, a double pair of oppositely disposed cams arranged to ride on the track, means for shifting the track to alternatively engage the cams, cylinder heads fixed to the cams, a weight slidably mounted in the cylinder heads whereby a water chamber is provided at either end thereof, an intake and a discharge tank at either end of the frame, hose connections between said tanks and chambers, means for causing said weight and cams to oscillate between the ends of the frame whereby suc-

tion is alternatively created in one of said water chambers and compression is alternatively created in the other chamber by said weight.

4. A pump comprising a frame, a track, a double pair of oppositely disposed cams arranged to ride on the track, means for shifting the track to alternatively engage the cams, cylinder heads fixed to the cams, a weight slidably mounted in the cylinder heads whereby a water chamber is provided at either end thereof, an intake and a discharge tank at either end of the frame, hose connections between said tanks and chambers, means for causing said weight and cams to oscillate between the ends of the frame whereby suction is alternatively created in one of said water chambers to draw the water from one of said intake tanks and compression is alternatively created in the other chamber to force the water into the discharge tanks, valve means for controlling the direction of flow of the water, means for restraining the movement of the rocker device at either limit thereof, and means for stopping the movement of the rocker device.

5. A pump comprising a frame, a track, a double pair of oppositely disposed cams arranged to ride on the track, means for shifting the track to alternatively engage the cams, cylinder heads fixed to the cams, a weight slidably mounted between the cylinder heads whereby a water chamber is provided at either end thereof, an intake and a discharge tank at either end of the frame, hose connections between said tanks and chambers, means for causing said weight and cams to oscillate between the ends of the frame whereby suction is alternatively created in one of said water chambers to draw the water from one of said intake tanks and compression is alternatively created in the other chamber to force the water into the discharge tanks, valve means for controlling the direction of flow of the water, means for restraining the movement of the rocker device at either limit thereof, means for stopping the movement of the rocker device, auxiliary electric motor driven water-motor means for the rocker device, and means for reversing said water-motor at predetermined times.

In testimony whereof I affix my signature.

EDWARD F. DARON.
